CONVERSION OF HYDROCARBONS

Hillis O. Folkins, Skokie, Ill., assignor to The Pure Oil Company, Chicago, Ill., a corporation of Ohio

Application March 15, 1944, Serial No. 526,538

6 Claims. (Cl. 260—683)

This invention relates to conversion of hydrocarbons and is more particularly concerned with a method for converting higher boiling hydrocarbons into lower boiling hydrocarbons and for making unsaturated hydrocarbons from saturated hydrocarbons.

I have discovered that if thermal conversion of hydrocarbons is carried out in the presence of a mixture of a phosphorous oxyhalide and oxygen or gas containing free oxygen, such as air, cracking of the hydrocarbons is greatly accelerated so that it is possible to obtain larger yields of cracked hydrocarbons under the same time-temperature-pressure conditions than it is possible to obtain by thermal cracking of the hydrocarbons without sensitizer, and it is possible to obtain yields at lower temperatures which are commensurate with yields obtainable at higher temperatures without sensitizers. My invention is applicable to either batch or continuous methods of cracking. In continuous cracking methods by operating under usual thermal cracking conditions in the presence of the sensitizer mixture, not only can increased yields be obtained, but higher octane gasoline can be produced. By using the sensitizer mixture, a larger throughput of charging stock for a given size unit can be effected because of the acceleration in the cracking reaction.

An object of my invention is to provide a method for conversion of hydrocarbons.

Another object of my invention is to provide a method for accelerating cracking of hydrocarbons.

Still another object of my invention is to provide a method for increasing octane number of motor fuel made by cracking of hydrocarbons.

A further object of my invention is to provide a sensitizer which will accelerate the decomposition of hydrocarbons.

A still further object of my invention is to provide a method for improving thermal cracking of hydrocarbons.

Other objects of the invention will become apparent from the following description and the accompanying drawing of which the single figure is a graphical representation of data showing the unexpected result obtained under certain conditions using sensitizer in accordance with my invention.

In accordance with my invention a small amount of phosphorus oxyhalide and oxygen or gas containing free oxygen, such as air, is mixed with the hydrocarbons subjected to decomposition. As phosphorus oxyhalides which are useful, may be mentioned phosphorus oxychloride, phos-

phorus oxybromide, phosphorus oxybromide dichloride, phosphorus oxydibromide chloride, phosphorus oxyfluoride and phosphorus oxyiodide. The phosphorus oxyhalide and the oxygen-containing gas may be mixed with the hydrocarbon prior to charging them to the reaction zone or they may be injected directly into the reaction zone. The total sensitizer mixture may be used in concentrations from approximately 0.5 mole percent to 6 mole percent based on the total charge and should not contain less than about .25 mole percent of the phosphorus oxyhalide or of oxygen. Higher concentrations of sensitizers may be used, but within the limits above set forth the reaction progresses satisfactorily without causing accumulation of undesirably large amounts of the sensitizers and their decomposition products in the motor fuel or other product which it is desired to produce. In my experimental work, I have found mole percentages ranging from approximately .5 to 3% of each sensitizer to give good results.

My invention is useful in conjunction with conventional types of thermal cracking in which the hydrocarbons are cracked at temperatures within the range of approximately 375° C. to 750° C. and is applicable to conversion of hydrocarbon gases such as propane and butane as well as to the conversion of liquid hydrocarbons such as heavy naphtha, kerosine and gas oil. A combination of the phosphorus oxyhalide and the oxygen-containing gas accelerates the cracking reaction to an extent in excess of that which would be expected from the cumulative effect of the phosphorus oxyhalide and the oxygen when each is used alone. In order to demonstrate this fact a number of runs were made using normal butane of 99% purity as charging stock. The runs were all made in a Pyrex glass reaction vessel at temperature of 525° C. Before starting each run, the reaction vessel was heated to 525° C. and then evacuated by means of a vacuum pump to a pressure below 0.001 mm. of mercury. Sufficient butane in admixture with the desired amount of sensitizer composition was then charged to the evacuated vessel until the pressure in the vessel approximated atmospheric pressure. The reaction was permitted to proceed in the closed reaction vessel while the temperature was maintained at 525° C. until a pressure increase of 25 percent above the initial pressure was observed, whereupon the reaction gases were removed from the reactor and analyzed.

A number of runs were also made without any sensitizer and runs were made using only phosphorus oxychloride and only oxygen as sensitizer.

Data for the runs is tabulated in the following table.

In each of the runs the initial pressure was calculated, a pressure reading was made 0.5 minute after the run began, thereafter pressure readings were made at intervals of 1 minute from the beginning of the run until 6 minutes thereafter, from that point readings were made at 2 minute intervals until 20 minutes after the run began and the run was terminated when the pressure increase had reached 25 percent. The figures appearing in the table for time required for 5% and 12.5% pressure increases are taken from curves based on the recorded data for pressure readings obtained as just described. The figures in the table for time required for 25% pressure increase represent recorded data.

The sensitization factors recorded in the tables are obtained by dividing the time required for a particular pressure increase without sensitizer by the time required for the same pressure increase with sensitizer.

were plotted with time in minutes as abscissae and percent pressure increase as ordinates.

Referring to the drawing, curve 1 is the curve for the average of blank runs to 299-B, 305-B and 309-B. Curve 2 is the curve for run 148-B using 1.0% of oxygen as sensitizer. Curve 3 is the curve for run 306-B using 1.0% phosphorus oxychloride as sensitizer. Curve 4 represents the hypothetical or cumulative results which would be expected from using 1.0% phosphorus oxychloride and 1.0% oxygen, and curve 5 is the curve for run 310-B in which 1.0% of phosphorus oxychloride and 1.0% of oxygen were used.

Curve 4 is obtained by adding the pressure increase without sensitizer at any selected time (curve 1), the pressure increase caused at the same time by the presence of oxygen alone (curve 2 minus curve 1) and the pressure increase caused at the same time by the presence of phosphorus oxychloride alone (curve 3 minus curve 1) and plotting on the graph the resulting sum for a sufficient number of time periods to

¹ 5% values inaccurate due to rapid initial rate.

By referring to Table I, it will be seen that both oxygen and phosphorus oxychloride alone accelerate the decomposition of butane. Whereas between twenty and twenty-one minutes were required to obtain a 25% increase with no sensitizer, 1.0% of oxygen caused a 25% pressure increase in 18.85 minutes and 2.0% caused a 25% pressure increase in 14.70 minutes. 1.0% of phosphorus oxychloride caused a 25% pressure increase in 17.83 minutes and 2.0% phosphorus oxychloride caused a 25% pressure increase in 15.05 minutes.

On the other hand, a mixture of 1.0% of phosphorus oxychloride and 1.0% oxygen brought a 25% pressure increase in 10.65 minutes; 1.0% of phosphorus oxychloride and 2.0% of oxygen caused a 25% pressure increase in 11.15 minutes; and 2.0% phosphorus oxychloride and 1.0% of oxygen caused a 25% pressure increase in 11.30 minutes. 1.0% of oxygen mixed with 1.0% phosphorus oxychloride was better than either 2.0% of phosphorus oxychloride or oxygen alone.

In order to demonstrate that the increase in acceleration of the reaction is greater than the additive, or cumulative effect of the sensitizers, curves were plotted for the various runs based on the pressure increases recorded at the aforesaid time intervals during each run and the curves

enable a curve to be drawn through the points. As an example, at 10 minutes after the run began, the pressure increase without any sensitizer obtained from curve 1 is 15.2%. At the same time the pressure increase for oxygen is 17.0% (obtained from curve 2) and the pressure increase for phosphorus oxychloride alone is 16.3 (obtained from curve 3). The pressure increase due to the presence of oxygen is, therefore, 17 minus 15.2 or 1.8%. The pressure increase due to the presence of phosphorus oxychloride is therefore 16.3 minus 15.2 or 1.1%. The cumulative pressure increase that might have been expected from the combination of phosphorus oxychloride and oxygen at the time of 10 minutes after the run began is the sum of the pressure increase at the same time without sensitizer and the pressure increases caused by each of the sensitizers, or 15.2 plus 1.8 plus 1.1 or 18.1 percent pressure increase. By referring to curve 4 it will be seen that this pressure increase has been plotted for the time of 10 minutes.

Comparing this with the experimental result obtained it will be seen that only 5.9 minutes were required to obtain a pressure increase of 18.1%. Thus, the reaction is accelerated about seventy percent over what would have been expected from the cumulative effects with oxygen and phosphorus oxychloride alone.

The expected times for 25% pressure increase and the experimental values obtained as well as the sensitization factors obtained experimentally and those which represent the additive effect of the phosphorus oxychloride and oxygen are given in Table II for runs 310-B, 311-B and 312-B.

TABLE II
n-Butane decomposition with phosphorus oxychloride and oxygen mixture at 525° C.

Run No.	Sensitizer		Time (mins.) for 25% ΔP values		Sensitization factors for 25% ΔP values	
	Name	Mole, per cent	Experimental	Additive	Experimental	Additive
310-B	(POCl ₃) _{1.0}	1.0	10.65	16.25	2.0	1.3
	(O ₂) _{1.0}	1.0				
311-B	(POCl ₃) _{1.0}	1.0	11.15	12.85	1.9	1.6
	(O ₂) _{2.0}	2.0				
312-B	(POCl ₃) _{2.0}	2.0	11.30	13.70	1.8	1.5
	(O ₂) _{1.0}	1.0				

It will be seen that the greatest increase in sensitization factor was obtained when 1.0% of phosphorus oxychloride and 1.0% of oxygen were used, but in every case a better sensitization factor was obtained than the expected additive or cumulative result.

The usual effect of the mixture of phosphorus oxyhalide and oxygen containing gas is further emphasized by the opposite effect obtained when using a mixture of phosphorus trichloride and oxygen. A run made with 1.0% phosphorus trichloride alone under the same conditions used in the runs, data for which is tabulated in Table I, required 10.73 minutes for 25% pressure increase, whereas in a run made with a mixture of 1.0% of oxygen and 1.0% of phosphorus trichloride, 11.27 minutes were required for a 25% pressure increase. Thus, the admixture of oxygen with phosphorus trichloride lowered the sensitization factor of the phosphorus trichloride instead of increasing it as in the case of phosphorus oxychloride.

It will be apparent from the analysis of reaction products given in Table I that the reaction is primarily one of splitting of the carbon to carbon bond as shown by the relatively large amount

of unsaturated hydrocarbon formed and the relatively small amount of hydrogen formed. The nature of the reaction products is essentially the same regardless of whether or not sensitizer is used.

The invention is useful in connection with known types of mineral oil, thermal cracking without catalyst. It is also useful in catalytic cracking operations wherein a solid comminuted catalyst, such as natural or synthetic alumina-silica compositions, is used. Invention may also be used in connection with cracking of gases to make unsaturated hydrocarbons, such as cracking of propane to ethylene, cracking of butane to ethylene and propylene as well as the cracking of liquid hydrocarbons to olefins or di-olefins such as butadiene.

I claim:

1. The method of converting hydrocarbons which comprises subjecting said hydrocarbons to suitable cracking conditions of time, temperature and pressure in the presence of a total of approximately 0.5 to 6 mole percent of oxygen and a phosphorus oxychloride.

2. Method in accordance with claim 1 in which the oxygen and the phosphorus oxychloride are each present in an amount of at least 0.25 mole percent.

3. Method in accordance with claim 1 in which the oxygen and phosphorus oxychloride are each present in an amount between 0.25 and 3 mole percent.

4. The method of cracking hydrocarbons having more than 2 carbon atoms per molecule consisting in subjecting said hydrocarbons to temperatures between approximately 375° and 750° C. in the presence of oxygen and phosphorus oxychloride in amounts not less than 0.25 mole percent of each.

5. Method in accordance with claim 4 in which the hydrocarbons contain a substantial amount of propane.

6. The method of cracking butane which comprises subjecting the butane to a temperature of approximately 525° C. in the presence of from 1 to 2 mole percent of oxygen and 1 to 2 mole percent of phosphorus oxychloride.

HILLIS O. FOLKINS.
